CLARENCE S. FAY, OF LOS ANGELES, CALIFORNIA.

THERMOSTATIC ELECTRIC SWITCH FOR FLATIRONS AND THE LIKE.

1,386,558.

Specification of Letters Patent. Patented Aug. 2, 1921.

Application filed October 4, 1919. Serial No. 328,580.

To all whom it may concern:

Be it known that I, CLARENCE S. FAY, a citizen of the United States, residing at Los Angeles, in the county of Los Angeles and State of California, have invented new and useful Improvements in Thermostatic Electric Switches for Flatirons and the like, of which the following is a specification.

My object is to make a thermostatic electric switch for flat irons and the like, and my invention consists of the novel features herein shown, described and claimed.

Figure 1 is a side elevation of a flat iron provided with a thermostatic electric switch in accordance with the principles of my invention, parts being broken away and shown in section to show the details of the switch.

Fig. 2 is a horizontal section on the line 2—2 of Fig. 1 and looking downwardly as indicated by the arrows.

Fig. 3 is a bottom plan view of the switch and a diagram of the electric circuit, as seen looking in the direction indicated by the arrow 3 in Fig. 1.

Fig. 4 is an enlarged fragmentary sectional detail of the snap feature of the switch, the view being taken on a plane parallel with Fig. 3 and on the line 4—4 of Fig. 1.

The flat iron 1 has a heating chamber 2 and an electric heating element 3 is mounted in the heating chamber 2 in the usual way. The body of the flat iron 1 is cast with an opening 4 at the center of its top. A plate 5 is fitted to cover the opening 4 and secured in place by screws 6 and the thermostatic switch 7 is mounted upon the lower face of the plate 5.

The details of the thermostatic switch 7 are as follows:

A post 8 extends downwardly from the plate 5, a thermostatic element 9 is rigidly fixed at one end of the post 8 and extends in a curve substantially once around the post 8 and some distance from the post and has fork tines 10 and 11 at its free end, the adjacent inner faces of the latter being covered with suitable insulating material such as hard rubber or fiber. (See Fig. 3.) The thermostatic element 9 is made of two strips of metal having different co-efficients of expansion.

The thermostatic switch blade 12 is mounted upon a pivot 13 and one end of the blade 12 fits between the insulated faces of the tines 10 and 11 so that as the thermostatic

element 9 expands and contracts the blade 12 is oscillated about its pivot 13.

A heart-shaped cam 14 is fixed to the blade 12. A leaf spring 15 is fixed to the plate 5 and has a yielding hump 16 in position to engage the point 17 of the cam 14. The electric line 18 connects the contact 19 of the socket 20 with a blade 21 having a contact point 22 in position to be engaged by the switch blade 12. A plate 23 is electrically connected to the switch blade 12 and the line 24 connects the plate 23 to one end of the electric heating element 3 and the other end of the electric heating element 3 is connected 70 to the terminal 25 in the socket 20.

When the flat iron is cold the tension of the thermostatic element 9 will snap the point 17 past the point 16 and swing the blade 12 against the contact 22 to close the circuit, and then if the cord plug 26 is in the socket 20 and the line 27 electrified the flat iron will heat until the temperature reaches a predetermined degree, whereupon the expansion of the thermostatic element 9 will 80 swing the switch blade 12 away from the contact 22 and snap the point 17 past the point 16 thereby opening the circuit and consequently stopping the heating operation.

Various changes may be made without departing from the spirit of my invention as claimed.

I claim:

1. A thermostatic switch for flat irons and the like, comprising a plate, a post extending 90 from the plate, a thermostatic element connected to the post, a pivotally mounted switch blade, one end of said switch blade being flexibly connected to the thermostatic element, a contact point in position to be engaged by the switch blade when the thermostatic element is cold, a cam carried by the switch blade and having a point and a leaf spring fixed to the plate, and having a yielding hump in position to be engaged by the 100 point of the cam so as to cause the switch blade to snap into engagement with the contact point by the tension of the thermostatic element.

2. A thermostatic switch comprising a 105 base, a convolute thermostatic element fixed at its inner end to the base, an electrically energized switch blade pivotally mounted on the base, one end of which is engaged by the outer free end of said element, its opposite 110 end normally engaging an electrically energized contact, and means to securely hold

said switch blade positively in and out of engagement with said contact when it is oscillated by expansion of the thermostatic element.

5. 3. A thermostatic switch comprising a base, a convolute thermostatic element fixed at its inner end to said base, an electrically energized switch blade pivotally mounted on said base and adapted to be oscillated by the 10 expansion and contraction of said element, one end of said blade adapted to engage the outer free end of said element, the opposite end normally engaging an electrically energized contact, resilient means to positively hold said blade in or out of contact with its 15 contact, said means comprising a pointed cam mounted on the blade, said point adapted to engage a leaf spring mounted on the base.

4. A thermostatic switch comprising a 20 base, a convolute thermostatic element, constructed of two strips of metal having different coefficients of expansion, fixed at its inner end to said base, an electrically energized switch blade pivotally mounted on 25 said base and adapted to be oscillated by the expansion and contraction of said element, one end of said blade adapted to engage the outer free end of said element, the opposite end normally engaging an electrically energized contact, resilient means to positively hold said blade in or out of contact with its contact, said means comprising a pointed cam mounted on the blade, said point adapted to engage a leaf spring mounted on the base. 30 35

In testimony whereof I have signed my name to this specification.

CLARENCE S. FAY.
